UNITED STATES PATENT OFFICE.

FRANK H. CRUMP, OF LOS ANGELES, CALIFORNIA.

EXCESS-BAGGAGE COUPON-CHECK.

No. 844,102.

Specification of Letters Patent.

Patented Feb. 12, 1907.

Application filed August 1, 1906. Serial No. 328,713.

To all whom it may concern:

Be it known that I, FRANK H. CRUMP, a citizen of the United States, residing at Los Angeles, in the county of Los Angeles and State of California, have invented a new and useful Improvement in Excess-Baggage Coupon-Checks, of which the following is a specification.

This invention is an excess-baggage coupon-check used in combination with any ordinary baggage-check and characterized by improved construction and novel means of attaching or associating same with the ordinary strap check or shell, so that after being attached the excess coupon-check can be opened or unfolded in order that one or more coupons may be removed by the baggage-man.

In the accompanying drawings, Figure 1 is a perspective view of an ordinary metal baggage-shell with an ordinary cardboard strap-check held therein, said check having attached thereto the excess-baggage check referred to. Fig. 2 is a longitudinal section of Fig. 1. Fig. 3 is a front perspective view of an ordinary cardboard check used without the shell and having the excess-baggage check fastened and folded on the back thereof. Fig. 4 is a rear perspective view of the same, with the excess-check unfolded. Fig. 5 is a face view of the excess coupon-check detached.

In the drawings, 6 indicates an ordinary metal baggage-shell with the side edges turned over, as at 7, to hold an ordinary cardboard check 8, which is provided with the usual destination and other marks on its face, the parts being held by a strap 9 passing through slots in the upper end of the shell and check.

The excess-baggage coupon-check shown in Fig. 5 is attached to the ordinary check and when used in connection with the shell is folded behind the same, as shown in Fig. 2. Said excess-check consists of a series or considerable number of coupons 10, containing proper tables or necessary printed matter, which is preferably so arranged that when folded one upon the other the amounts or spaces register with each other, so that one punch put through two or more of the folds will indicate the same amounts on all the coupons. This is done by printing the tables in reverse order on the alternate coupons. At the upper end the check has a gummed tab 13, by which it may be attached

to the back of the cardboard check, as shown in Fig. 4. After being punched and attached it is folded against the back of the regular check and the whole then slipped into the metal shell or holder, with the excess-coupons between the cardboard and the metal, as shown in Fig. 2. This may be pushed out of the shell and back again by the train baggageman for the removal of a coupon. When folded and in the holder or shell, the coupons are protected and securely held, but are readily accessible at any time.

For use with a check without a holder, as shown in Figs. 3 and 4, fastening means are provided for holding the excess-check in folded position on the back of the usual check. The tab 13 of the coupon-check is stuck on the back of the cardboard check 8, and the coupons 10 are provided with holes 14, which register when the coupons are folded to receive the prongs of a fastener 16, which is secured to the cardboard check, as by teeth 17 stuck therein, and this fastener also serves to attach the usual twine loop 18 by which the check is attached to a piece of baggage. The prongs can be quickly and easily bent up to enable the train baggageman to remove the coupons desired and to again close the fastener and secure the remaining coupons. Such a check is preferably reinforced by linen backing, as shown at 20, to prevent the fastener or cord pulling out.

In any of the forms the excess-baggage coupons are securely held to the check to which they belong, thereby avoiding mistakes and loss. The excess-check is preferably made of flexible paper, so that it can be readily folded and punched and run through a ticket-dating or hand stamp, and provided with perforated lines between the coupons, so that they can be readily separated.

I claim—

The combination with an ordinary baggage-check, of an excess-baggage check secured thereto and having a series of coupons provided with perforations which register when said coupons are folded, and a fastener secured to the back of the ordinary check and having prongs which may be inserted through said perforations to hold the coupons.

FRANK H. CRUMP.
